Primary Examiner — Jennifer L Watkins*Assistant Examiner* — Samantha Lynne Brodowski(74) *Attorney, Agent, or Firm* — Lowe Graham Jones PLLC(57) **CLAIM**

I claim the ornamental design for a rolling case, as shown and described.

DESCRIPTION

The sole FIGURE is a perspective view of the rolling case, showing my new design.

The broken lines depict portions of the article and form no part of the claimed design.

1 Claim, 1 Drawing Sheet(56)
